UNITED STATES PATENT OFFICE.

LOUIS M. HOOPER, OF RUTHERFORD, NEW JERSEY, ASSIGNOR TO THE J. L. MOTT IRON WORKS, OF NEW YORK, N. Y.

SPRAY-BATH.

SPECIFICATION forming part of Letters Patent No. 585,439, dated June 29, 1897.

Application filed May 8, 1895. Serial No. 548,533. (No model.)

To all whom it may concern:

Be it known that I, LOUIS M. HOOPER, a citizen of the United States, residing at Rutherford, in the county of Bergen and State of New Jersey, have invented an Improvement 5 in Spray-Baths, of which the following is a specification.

This invention relates to that class of baths in which there are perforated pipes for spraying the person receiving the bath. The water can be turned onto the spray or needle-jets or from the shower, so that numerous small jets of water run down the person, or it may come from a central pipe or douche that supplies a large volume of water vertically upon 15 the person; or the water may come from roses or finely-perforated nozzles, usually known as the "liver-spray," or the water may be directed upwardly from a "bidet-bath."

20 The present improvements relate to the peculiar combination of devices whereby the apparatus is simplified in construction and lessened in expense, and it is more easily managed than the devices heretofore employed, because the cocks and connections 25 are easy of access to either the attendant or to the person taking the bath.

In the drawings, Figure 1 is a perspective view illustrating the general character of the 30 apparatus. Fig. 2 is a section through the pipes and connections to the respective valves. Fig. 3 is a section of the tubular connection for the bidet. Fig. 4 is a vertical section representing the devices for connecting 35 the needle-spray tubes with the horizontal tubes. Figs. 5 and 6 represent the wedge that is made use of at the upper connection for such needle-spray tubes, and Fig. 7 is a section in larger size of the shower- 40 bath head and douche.

The hot-water-supply pipe at A and the cold-water-supply pipe at B are connected together through the cocks or valves C and D with the vertical mixing-column E, from 45 which pass off laterally the pipes G, H, I, K, and L, each pipe being provided with a cock connecting it with the mixing-column, and by which the water of the desired temperature is allowed to pass through one or more 50 of these branch pipes.

The combination-bath apparatus is usually

placed in a recess, in which M represents the back wall, and N N' side walls, and the vertical columns O, O', and O² are supported by collars upon the floor P and by bracket-arms 55 at Q, and the upper part of the pipe O is connected with and opens into the shower R, and the upper end of the pipe O² is connected with and opens into the douche or single-jet pipe S. There are segmental or horizontal 60 pipes T, T', and T² extending around between the pipes O, O', and O² and connected at their ends by globular couplings a, as illustrated in Fig. 1, and the needle-spray tubes U stand vertically and are supported from 65 the segmental tubes T and T², and upon the tube T' are the rose or liver spray projections V.

A combination-bath arrangement approximating the devices thus far described will be 70 found in Letters Patent No. 335,785, and the special features of the present invention relate to the peculiar connections of the respective pipes as next described, whereby the parts are rendered more simple and easier 75 to construct than the baths of this character heretofore made.

Upon reference to Fig. 2 it will be seen that the pipe or column O is stopped off just below the inlet-pipe K, and hence the water 80 admitted through the pipe K from the mixing-chamber E passes up the upper portion of the column or pipe O into the shower R.

The water admitted by the pipe and cock L passes into one of the globular connections 85 a and around the pipe or column O and along by the upper segmental pipe T² to the upper part of the column O² and hence to the douche S, there being an angular elbow, as illustrated in the diagram Fig. 2, between one 90 portion of the pipe T² and the upper part of the pipe O².

The water admitted by the pipe and cock I passes into the column O and by the lower segmental pipe T to the column O² and to the 95 column O', and it also passes to the spray-pipes U U, as illustrated in this diagram Fig. 2, there being perforations represented in the pipes O, O', and O² between the segmental pipes T and T². It is, however, to be understood that in Fig. 2 the connections between 100 the segmental pipe T and the spray-tubes U

are only diagrammatic and that the specific connection is hereinafter described.

When the roses or liver-sprays V are made use of, the water is turned on through the pipe H and passes into one of the globular connections a around the pipe O and by the segmental pipe T' to such liver-spray V.

In order to properly support and connect the vertical spray-tubes U with the respective segmental or horizontal tubes T and T², I make upon each spray-tube V a branch connection 10 and a union 11, connecting the same with a branch 12 from the pipe T, so that water passing through such pipe T, as before indicated, will also pass into the vertical spray-pipes U and issue in small jets through the holes therein, and for supporting the upper portion of each spray-tube U, I provide a stud or arm 14 for each of such spray-tubes U, the same projecting from the pipe T², and in the outer surface of each arm 14 is a dovetailed recess adapted to receive a dovetailed block 15, that is soldered or otherwise fastened upon the back of the pipe U, so that as the pipe U is applied in its place the block 15 is pressed up into the recess in the arm 14 and the ends of the branches 10 and 12 are brought together and the screw-union 11 employed to connect the parts, and I find it advantageous to place the block 15 at a slight inclination, as illustrated in Fig. 6, so that the block may be caused to bind in its dovetailed recess. If the pipe is passed upwardly into its position at a slight inclination and then brought vertical as the union is screwed up, such block will bind firmly in its recess. By this arrangement the needle-sprays, the liver-sprays, the shower, or the douche can be directed upon the person taking the bath either simultaneously or separately, so that the water runs down the person, and the bidet attachment W is upon an arm 18, extending out from the vertical pipe 19, which vertical pipe is free to be turned in the supports 20, that extend out from the column O, and at the upper end is a connection from the pipe 19 to the branch pipe G, as illustrated in larger size in Fig. 3, the upper end of the pipe 19 being formed as a plug 50 similar to an ordinary cock and the pipe 19 being provided with a handle 22, so that the pipe 19 can be turned by the handle 22 and the bidet attachment W swung out over the center of the floor of the bath, so that a jet or jets of water can be employed from the bidet to act upwardly in washing the person, and when swung back into the position shown in Fig. 1 the supply of water may be cut off by the plug in the upper end of the pipe 19 even without actuating the valve to the branch pipe G.

In cases where it is desired to regulate the admission of water to the bidet the valve in the pipe G may alone be employed, in which

instance the plug at the upper end of the pipe 19 will be made, as shown, with a groove around it, so that the movement of the plug in the ball at the end of the pipe G will not open or close the water passage-way.

Instances sometimes arise where the perforations in the shower-bath R become obstructed, and it is difficult to clean the hollow head forming the shower-bath. To allow for the removal of the shower-bath head, in which are the numerous perforations, I provide a screw-threaded hub s, adapted to fit a screw-threaded opening in the upper part of the case of the shower, so that the case and the perforated plate forming the shower-bath can be unscrewed from the hub or supports for cleaning or for repairs, and in cases where the douche S is made use of it is advantageous to provide a removable nipple i at the lower end of the douche-pipe screwed into the lower part of such douche-pipe above the perforated plate of the shower, so that by unscrewing this nipple the shower-bath head can be removed by unscrewing the same from the hub s.

I claim as my invention—

1. The combination with needle-spray tubes and roses and the shower and douche, of the tubular column O with an internal stop and branch pipes I and K above and below the stop and the pipes to the needle-spray tubes and the shower respectively, the branch pipe L and the globular connection around the column and the pipe to the douche, and the branch pipe H and globular connection to the spray-roses, substantially as set forth.

2. A rose-nozzle consisting of a lower perforated part and an upper part which expands downwardly these two parts being detachably connected for convenience in cleansing the interior, substantially as specified.

3. The combination with the horizontal pipes and the vertical needle-spray tubes, of branch pipes and unions for connecting the needle-spray tubes to the supply water-pipe, and dovetailed blocks and recesses for supporting the needle-spray tubes to the other horizontal pipe, substantially as set forth.

4. The combination with the horizontal pipes and the vertical needle-spray tubes, of branch pipes and unions for connecting the needle-spray tubes to the water-supply pipe, and blocks received into recesses upon supporting arms for holding such needle-spray tubes, such blocks being at an inclination so as to bind in their recesses when the needle-spray tubes are brought into vertical position for coupling to the water-supply pipe, substantially as set forth.

Signed by me this 6th day of May, 1895.

L. M. HOOPER.
